[57] CLAIM

The ornamental design for a tumbler or similar article, substantially as shown and described.

DESCRIPTION

FIG. 1 is a side elevational view of a tumbler or similar article showing my new design, all sides being the same;

FIG. 2 is a top plan view thereof;

FIG. 3 is a vertical cross-sectional view thereof, taken along line 3—3 of FIG. 2;

FIG. 4 is a bottom plan view thereof;

FIG. 5 is a horizontal cross-sectional view thereof,
taken along line 5—5 of FIG. 3;

FIG. 6 is a horizontal cross-sectional view thereof, taken along line 6—6 of FIG. 3; and

FIG. 7 is a horizontal cross-sectional view thereof,
taken along line 7—7 of FIG. 3.
